LAMINATED WOODEN PLATE

Gustaf Kähr, Nybro, Sweden

Application October 9, 1936, Serial No. 104,897
In Sweden October 19, 1935

3 Claims. (Cl. 20—91)

My invention relates to so called laminated wooden plates consisting of a core of wood and of surfacing sheets of a cross-veneer or the like applied on opposite sides of the core.

It is an object of my invention to provide a plate of this kind which is not subject to warping and which possesses good sound insulating properties.

Laminated plates of a similar kind are known in which the core consists of a single compact block of wood which, in order to avoid warping, is cut in on opposite sides, the cuts or incisions extending perpendicularly to the direction of the fibres. Notwithstanding this such a plate is liable to swelling in a direction along the plane of the plate transversely of the fibres. If such plates are made of hard wood, for instance oak, which is desirable for obtaining a high sound insulating capacity, the plate, in spite of the incisions, will possess a considerable residual elasticity which may cause warping of the plate.

According to the present invention I compose the core of a plurality of parallelly disposed rods or laths, in which the fibres extend substantially in parallel with the surface of the plate and longitudinally of the rods, and I sever or cut the fibres by making incisions alternately from opposite sides of the rods, such incisions extending through part of the rods only. Due to the interstices between the rods tensioning of the plate in a direction perpendicular to the direction of the fibres is thereby prevented. When composing the core of a plurality of rods it becomes possible at the same time to remove more completely the spring effect of the wood by cutting the fibres through by means of incisions extending inwardly from more than two and preferably from all four sides. This latter arrangement is of particular importance with hard woods, the spring effect in which cannot be removed entirely by the arrangement of incisions extending from two opposite sides only.

The invention will now be described more in detail, having reference to the drawing affixed in this specification and forming part thereof which shows in a diagrammatic manner by way of example an embodiment of my invention.

In the drawing

Figure 1 is a section of part of the plate on the line 1—1 in Figure 2.

Figure 2 is a plan view of the plate with the uppermost surfacing layer removed, and

Figure 3 is a cross-section.

Figure 4 is a similar view of a modified form.

Figure 5 illustrates a detail on a larger scale.

Referring to the drawing 1 are the rods forming the core of the plate, which are positioned in parallel with each other between parallel planes and are spaced somewhat, interstices 2 being formed between them. The ends of the rods are formed with tongues 3 which fit into corresponding grooves in transversely extending edge laths 4 which together with side laths 5 form a reinforcing frame, which holds the parts together. If such a frame is provided it is not necessary to fit the ends of the rods into the frame by means of tongues or the like, but obviously the mechanical strength of the plate is increased thereby. Glued onto opposite sides of the core are surfacing sheets 6 of cross-veneer, plywood, masonite or the like. The rods 1, which have a rectangular cross-section, are formed with incisions 7 of considerable depth, which extend alternately from the four sides through the greater part of the thickness of the rods so that each rod still forms a coherent unit. In the example shown in Figure 2 the uppermost incisions 7, thus extend from the top sides of the rods, the other incisions starting from the right hand side, from below, and from the left hand side of each rod, respectively. The side laths 5 are formed with incisions 8 starting from the inner side only.

Owing to the provision of the incisions 7 the fibres are cut through at a plurality of points, thereby losing the capacity of setting up internal stresses in the wood through contraction or expansion in the longitudinal direction. The incisions may also extend from two sides of the rods only, depending upon the kind of wood used. A more even and complete equalizing of the internal strains is obtained, however, if the incisions, as in the embodiment shown in the drawing, extend alternately from all four sides.

The incisions 7 in the rods 1, as well as the incisions 8 in the side laths 5 are filled with a filling material, for instance a binder 10 (Fig. 5). I prefer using glue or some other suitable substance capable of preventing the rods from being weakened by the incisions. Actually the rods, after complete solidification of the glue, possess considerable strength at the points of incision. I prefer filling the binder into the incisions immediately before the core is fitted together and the surfacing sheets 6 placed in position, so that the binder will set, while the plate is subjected in 50 the usual manner to heavy pressure in a hydraulic press or the like, and simultaneously with the pressing-on of the surfacing sheets 6.

In order to prevent that, when pressing the plate together, the sheets 6 are forced into the

gaps 2 between the rods, whereby the surface of the plate would become uneven, the rods 1 can be arranged in close juxtaposition, as shown in Figure 4, the adjoining faces of the rods being hollowed out, so that the rods will bear against each other only along comparatively narrow edges 8, being partly separated by longitudinal cavities 12.

No reinforcing frame need surround the core, 10 however in that case I prefer to cover the lateral edges of the plate if they should be formed with cavities 12, with laths or strips 16 of cross-veneer or the like.

In order to increase the sound insulating 15 capacity of the plate I may fill the gaps 2 with an elastic sound insulating material, such as paper board in the form of strips or the like.

Plates according to this invention can be used in the construction of doors, table tops, the side 20 walls of cupboards or the like, or as wall covering material.

I wish it to be understood that I do not desire to be limited to the exact details of construction shown and described for obvious modifications will occur to a person skilled in the art.

I claim:

1. A laminated wooden plate comprising in combination, a plurality of rods arranged in parallel juxtaposition and a surfacing sheet covering the row of rods on either side, the fibres in said rows extending substantially in the longitudinal 10 direction of the rods, the rods being formed with incisions extending alternately from all four sides of the rods to a depth such as to effectively sever the fibres at spaced intervals.

2. The laminated plate of claim 1, in which the 15 rods are formed with a rectangular cross section.

3. The plate of claim 1, in which a binder is arranged in the incisions.

GUSTAF KÄHR. 20
